PNEUMATIC DUST REMOVAL MACHINE

John G. Hollick, Beverly, Mass., assignor to United Shoe Machinery Corporation, Flemington, N. J., a corporation of New Jersey

Application March 30, 1949, Serial No. 84,368

12 Claims. (Cl. 69—1)

1

This invention relates to machines for removing dust particles from the surfaces of materials which are handled as individual sheets and which possess compact structures as distinguished from loose structures such as fabrics. The invention relates more particularly to pneumatic apparatus for removing fine dust from such articles as tanned hides or skins. As herein illustrated, the invention is embodied in a pneumatic machine which is an improvement over that disclosed and claimed in a copending application for Letters Patent of the United States Serial No. 740,666, filed April 10, 1947, in the names of Cutler D. Knowlton and John G. Hollick, which issued on September 27, 1949 as Patent No. 2,482,781. Such machines are particularly adapted for carrying out the novel method disclosed and claimed in a copending application for Letters Patent of the United States, Serial No. 691,090, filed August 16, 1946, in the name of John G. Hollick, which issued on September 27, 1949 as Patent No. 2,482,775.

Conventional brushing machines (relying upon brushes for the actual cleaning operation) do not remove dust from leather to the extent desired with the result that subsequent operations often produce a cloudy, streaked or unsightly finish on the leather.

The pneumatic machine disclosed in the patent application Serial No. 740,666, above referred to, has been found in actual tannery practice to perform superior work and in a manner not previously encountered in a tannery. It has been found, however, that in the use of such a pneumatic machine there often are difficulties in feeding, particular leathers having stiff or curled edges or which are extremely flexible or flimsy such as suede (sheepskin) or very thin calfskin. If one brush is used for feeding the work, then the work must be pushed (instead of being pulled) during a portion of its travel through the machine and the feeding becomes erratic. If two brushes are used to feed the work (one brush for each side of the work as the other side is cleaned by air), then neither brush performs its work in a positive manner and difficult timing problems arise together with the added expense of the requisite parts. At least one brush was used and was believed preferable in the pneumatic type of machine to bring about the feeding of each consecutive work piece, such as a hide or skin, through the machine and it was shown to be effective in this respect for some leathers but not for others and its use on all leathers was not such as to make the pneu-

matic dust removal operation as efficient as would be desirable. Another difficulty has been encountered in that certain passages of the pneumatic machine have been blocked with dust, causing frequent interruptions in the production schedule and making cleansing of the machine necessary.

An object of the present invention is to provide a pneumatic machine for removing dust from consecutively presented work pieces such as hides or skins in which machine the work may be more smoothly fed to and from a treatment zone with improved efficiency of dust removal in that zone despite variations in thickness, flexibility or stiffness necessarily encountered in such work.

To the above ends and in accordance with important characteristics of the invention, a flexible conveyor belt is provided for guiding and resiliently restraining a spread-out work piece in a path contiguous to a nozzle discharge area and a suction duct structure associated with that area. Preferably, and as illustrated, two similar units—i. e., two nozzle and suction structures are provided, one for each side of a work piece to be treated, and each unit has a flexible belt conveyor cooperating with it.

Another feature of the invention is found in each unit or nozzle and suction structure which comprises two halves or castings joined together with spacing means between them to determine the nozzle discharge area or opening which is preferably in the form of a slot. One other feature resides in the stepped and slotted nozzle structure in which the nozzle lip located nearest to the front of the machine extends nearer to the path of the work than the other lip of the same unit. Still another feature is the provision for supplementing the dust-laden air with more air to insure the carrying away of the dust from the nozzle and suction passages of the machine.

As a further feature the invention provides a safety device whereby the inadvertent insertion of an operator's hand or some object, the presence of which is not desirable, into the machine will automatically terminate the work feeding operation of the conveyor and which, preferably, will automatically reverse the direction of travel of the conveyor to eject the hand or object.

When the term "hides" is used alone herein it is the intention to refer to work pieces such as hides, sides, or skins. The use of that term avoids excess verbiage.

The invention will now be more particularly described by reference to the accompanying drawings and thereafter pointed out in the claims.

In the drawings,

Fig. 1 is a front view in elevation and partially in section (along the line I—I of Fig. 2) of the preferred form of the apparatus;

Fig. 2 is an elevation view of the right-hand end of the machine shown in Fig. 1, parts being broken away for purposes of illustration;

Fig. 3 is an enlarged sectional view along the line III—III of Fig. 1 and is drawn to a larger scale with the main operative parts of the machine being shown;

Fig. 4 is a plan view of the left-hand end of the lower nozzle and suction structure or unit together with portions of conveyor belts associated therewith;

Fig. 5 is a perspective view in section and diagrammatically presented to illustrate the principles of operation of the machine;

Fig. 6 is an enlarged sectional view of a portion of one nozzle and suction structure;

Fig. 7 is a view partially in section and drawn to an enlarged scale of some of the safety device details shown in the left-hand side of the machine as viewed in Fig. 1;

Fig. 8 is a view in perspective showing a portion including one end of a casting, which casting comprises almost one half of a complete nozzle and suction structure; and

Fig. 9 is a perspective view of some of the parts shown in Fig. 4;

Fig. 10 is a perspective view of a locator or gage mechanism for the front conveyor belt roller; and

Fig. 11 is a diagrammatic representation of the electrical control system for the conveyors.

The machine includes a right-hand cast iron standard 10 (Fig. 1) and a left-hand cast iron standard 12 between which and upon which are supported two horizontally extending nozzle and suction structures A and B. A conveyor system made up of three endless conveyor belts 14, 16 and 18 (Figs. 2, 3 and 5) and their supporting rollers 20, 22, 24, 26, 28 and 30 are arranged for the conveying of a work piece W (Fig. 3) beneath the nozzle structure A and just above the nozzle structure B and from the machine.

The upper nozzle and suction structure A is supported on the standards 10 and 12 by bolts 32 (shown only at the right-hand end of the machine in Figs. 1 and 2). The nozzle and suction structure B is supported on the standards 10 and 12 by bolts 34 (also shown at one end only of the machine).

The nozzle and suction structures A and B are identical in construction and each is made up of two castings 36 which are similar in that they may be taken from the same mold. Each casting 36 is rather intricate in construction and may best be understood by reference to Fig. 8. The ends of a given casting 36 are similar to each other except, of course, that they are to the opposite hand. Each of the castings 36 is made up of a side or vertical wall 40, a horizontal wall 42, end walls 44, a nozzle wall section 46, and interior partitions 48, 50, 52, 54 and 56. The partitions are so arranged, when two of the castings 36 are joined together to form a unit, that air entering through end openings 60 (in this case through only one opening 60 of each unit A or B) is caused to flow along between the nozzle wall sections 46 and emerge from between the lips 62. After im-

pact with leather to be cleaned, as will be further described, dust-laden air is then caused to pass between parallel ribs or partitions 64 and out through a central discharge opening 66. The above-referred-to passage of air obtains when two halves 36 are bolted together in the relation shown in Figs. 2 and 3. Each end of each casting 36 is provided with five through holes 70 (Fig. 8) for bolts 72 which serve to hold the two halves of a nozzle unit or structure A or B together. Each casting 36 is also provided with holes 80 (Fig. 8) passing through the partition 52 and through which bolts 81 (see unit A in Fig. 3) are retained to aid in holding the two halves 36 together. As will be further explained the two halves are not in contact with each other when assembled but are separated a short distance by thin sheets of metal or shims 82 and 84 and also by a gasket or filler composition 85 at exterior points where the shims are not used. Each casting 36 is also provided with a number of bosses 88 (Figs. 3 and 8) through which pass bolts 90 (see unit A in Fig. 3) which assist in holding the parts in rigid relation. The ribs 64 of each casting are parallel and they are inclined at an angle across the casting. Side plates 100 are attached to the castings of each unit by means of screws 104. It will be noted that the ribs 64 are each of such length that they form passages leading from one side of each wall 100 to the exterior or other side of that wall. The longitudinal edge 110 of each casting 36 is beveled as shown. In the machine illustrated, the four openings 60 and the two openings 66 of the two front castings 36 are closed by means of plates 112 and 114. The rear right-hand opening 60 of the unit A communicates with a rubber hose 120 (Fig. 2) leading to a source of supply of air under pressure. The lower rear and left-hand opening 60 communicates with a source of air under pressure by means of the hose connection 122. The rear left-hand opening 60 of the unit A and the rear right-hand opening 60 of the unit B are closed by means of suitable plates. The upper opening 66 communicates with an air exhaust system by means of a conduit 124 and the lower rear opening 66 communicates with the same system by the conduit 126.

A switch control box 130 (Fig. 1) is mounted on the front of the machine and has three push buttons F, R and S for initiating operation of the work feeding system forwardly or in reverse or for stopping it.

A casting 132 is mounted near the right-hand end and on the under side of the nozzle structure A and is attached thereto by bolts not shown. A similar casting 134 (but to the opposite hand) is mounted near the other end of the nozzle structure A. These castings are arranged to serve as journals or bearings for the conveyor roller 24 and a freely rotatable roll 136 covered with rubber, plush or short bristles. The foremost conveyor roller 20 is supported in two bearings 140 (Fig. 2) and 142 (Fig. 1) which are in turn suspended from the brackets or castings 132 and 134 by means of bolts 144 and 146. Each of the bolts 144 and 146 passes through a slot in its casting 132 or 134 permitting adjustment of the roller 20 to vary the tension in the belt 14.

A handle 150 (Figs. 2 and 10) depends from and is pivoted upon a pin 152 passing through two ears 154 and 156 (Fig. 10) forming part of the casting 132. A rod 158 is threaded into the upper end of the handle 150 and is locked therein

in such position as to abut the rear of the journal 14 and thereby adjustably determine the proper position of the right-hand end of the roller 20 as well as the proper tension in the belt 14 preliminary to tightening of the bolt 144. The journal 142 is similarly mounted for adjustment and a handle 160 (similar to handle 150) is shown for the purpose (see Fig. 1). With the construction of these details as shown, the tension of the belt 14 may be restored after cleaning of the slot in unit A and this restoration may be effected without tedious adjustment. In other words, the pins 158 serve as locators or gages in positioning the roller 20. If the handles 150 and 160 are swung forwardly and the bolts 144 and 146 are loosened, the belt 20 may be relaxed sufficiently to permit insertion of an appropriate tool to clean the air discharge slot of the unit A.

Beneath the upper run of the forward conveyor belt 14 and directly below the rubber covered roll 136 is a bar or tube 162. This bar is slightly longer than the full width of the belt 14 and is provided with end extension pieces 164 (Fig. 7) and 166 (Fig. 2) for supporting the same. Only one extension piece, 164, will be described as they are identical. The piece 164 is adapted to slide vertically on a rod 170 which is threaded into the casting 184. Two stop collars 174 and 176 are attached to the rod 170 to determine the limits of vertical travel of the bar 162. The extreme end of the extension 164 is provided with an eye 178 by means of which a spring 180 is adapted to resiliently support the bar 162 to an eye 182 affixed to the stanchion 12. A micro-switch 184 is attached to the stanchion 12 with its plunger normally in contact with the extension 164. A spring 186 and micro-switch 188 (Fig. 11) are similarly mounted at the other end of the bar 162.

Two brackets 200 are mounted on the nozzle structure B to support and form journals for the two conveyor rollers 22 and 28. Each bracket 200 is attached to the nozzle structure B by three bolts 202 (Fig. 4) and is provided with a horizontal rear extension 204 (Fig. 9) and an upwardly directed flange 206. A threaded rod 208 passes through each flange 206 and is provided with a lock nut 210 (Fig. 2). This mechanism permits a horizontal adjustment in and determination of the position of the roller 26 as the threaded rod 208 abuts against one of the journals 212 at each end of the roller 26. Each journal 212 is attached to its bracket extension 204 by means of a bolt passing through a slot 213 (Fig. 9) in that extension.

An outrigger arm 220 extends rearwardly from each end of the nozzle mechanism B and is attached thereto by two bolts 222. Each arm 220 has a depending projection 230 (Fig. 2) with a screw and nut arrangement 232 for adjusting to a slight extent the slight angle which may be found necessary between the arm 220 and the horizontal. A journal 240 is adjustably mounted at the rear of each arm 220 for the support of the conveyor roller 30. The outrigger arms 220 and the third belt 18 comprise optional equipment the use of which is preferred but is not essential as will further appear.

A large bracket 250 (Fig. 1) is bolted at 252 to the front side of the nozzle mechanism B and to this bracket is attached the motor M for driving the conveyor system. The motor shaft is arranged to drive a pulley 254 through a gear arrangement 255. A belt 257 leads from the pulley 254 to a pulley 258 which is keyed to rotate with

the roller 24. A gear 260 is pinned to the shaft of the roller 24 to rotate with it and thereby rotate the roller 22 by engagement with a gear 262 pinned to the latter. The roller 28 is provided with a sprocket 264 and the roller 22 bears a sprocket 266. The two sprockets 264 and 266 and their rollers 28 and 22 are connected and rotated together by means of a chain 268. It will be understood that belt 14 is driven by the roller 22, that belt 18 is driven by the roller 28, the ends of all conveyor shafts are provided with collars 269 where essential.

It has been stated above that the four castings 36 are identical and this is substantially correct as they are made from the same mold. It has been found, however, that the rear halves or castings of each nozzle structure A or B should be modified slightly in order to minimize the clogging of the nozzle discharge areas. It has been found advantageous to machine down the lip of the rear castings 36 as clearly illustrated in Fig. 6. This provision eliminates the possibility of dirt being forced into and any work catching in the slot of the particular nozzle structure concerned. The slot width dimension P (Fig. 6) should not exceed $\frac{1}{2}$ of an inch and with such a slot the distance J should be at least .005 inch if the desired non-clogging propensities of the slot are to be realized. It is much preferred that such orifice be in the form of a slot and that the preferred effective width of the slot be only a few thousandths of an inch, that is, not in excess of $\frac{1}{1000}$ of an inch. With such a dimension for the width, the slot is barely perceptible to the eye. Regardless of the form of orifice or orifices used (it is clear that perforated stationary or reciprocated nozzle members may be used in lieu of slotted units) the effective cross sectional orifice area should not exceed $\frac{1}{2}$ of a square inch per linear foot (measured transverse to the direction of feed of the work)—which is the same as the area of a $\frac{1}{2}$ " slot.

A guard 300 of sheet metal is mounted on the front of the unit A and is attached thereto by screws 302. The guard is provided with a downwardly and rearwardly inclined lip 304 which terminates close up to the soft covering of the roller 136.

In operating the machine the motor M is utilized to run the conveyor system in a direction shown by the arrows in Figs. 3 and 5. A hide W (Fig. 3) is then spread out by the operator upon the upper run of the conveyor belt 14 and one edge thereof is inserted beneath the rubber-covered roller 136. The insertion is made easy by the presence of the guard lip 304. Assuming that air under pressure is directed into the nozzle structure A and B through conduits 120 and 122, the work piece W is quickly and positively fed by the conveyor system beneath the nozzle area of the unit A and over the nozzle area of the unit B and then is discharged to the conveyor belt 18 from which the cleaned work piece W may

be removed. During the passage, the air emerges from the slot of each unit A and B and impinges upon the leather to dislodge dust therefrom. The dust-laden air is pulled into the exhaust system from both sides of each slot through the spaces between the ribs 64. Supplementary air from the room is admitted at the side of each unit to those same spaces and ensures sufficient air velocity to carry the dust out of the machine.

The belt 18 serves to support each treated work piece momentarily, permitting the operator suffi-

cient time to remove it before it contacts the floor or parts of the machine. Satisfactory operation is assured without the belt 18, however, for the operator may grasp the leading edge of each work piece and may manually support the piece as it is discharged.

Fig. 11 diagrammatically illustrates the electrical circuits utilized in controlling the motor M for driving the conveyor belts of the machine. Power is derived from the main lines D, E and G, the three-phase current passing only to the motor M.

For feeding a work piece through the machine—i. e., for moving the conveyor belts 14, 16 and 18 forwardly, the push button F is depressed, energizing the forward contactor FC which remains energized when the button F is released because of the holding contacts C. Current passes through the lines d, e and g to the motor M.

When an obstruction, such as the hand of an operator, causes the upper run of the conveyor belt 14 to be depressed beyond a predetermined limit, one or both of the switches 184 and 188 will close, energizing the relay K and opening the coil of the forward contactor FC thereby shutting off the power to the motor M. After a short time delay due to the mechanism of the relay K, the reverse contactor RC is energized and the motor M actuates the conveyors in reverse. Reverse operation removes the operator's hand or other obstruction from the zone above the bar 162, ensures that both switches 184 and 188 are open and stops the motor M. The push button F must again be depressed for resumption of the work feeding operation.

With the circuits shown, the motor M and the conveyors which it drives may be stopped by depressing the bush button S or they may be operated in reverse for such interval of time as may be desired depressing the reverse push button R to energize the reverse contactor RC. With current flowing the mechanical linkage or pivoting lever H between the contactors FC and RC forces the motor M to run either forwardly or in reverse.

It has been found that solid matter may sometimes lodge in the nozzle discharge area or slot of the nozzle structure A because of the small width dimension of the slot and because of the effect of gravity. In order to facilitate removal of such obstructions the conveyor roller 20 may be loosened from its position and pushed rearwardly a sufficient amount to permit an operator to put his hand into the machine between the roller 136 and the bar 162 and insert a thin instrument into the discharge slot to clean it. This operation has been referred to above in the description of the handles 150 and 160 and their function.

The cleaning of each individual work piece is rapidly done and the effective cleaning action of the air at each nozzle unit is limited to and concentrated on the leather area immediately adjacent the air discharge slot of each unit. With such concentration of the air currents on the work piece the action is extremely effective and serves to minimize the quantity of air essential for the proper dust removal. It is known from actual operation that the air action is concentrated on the areas referred to. This is because of the efficiency of operation and also because of the visual evidence that the surfaces of the edges 110 contacted by the work and the corresponding conveyor belt become more polished than do the webs 64. It will be noted that the conveyor

belts 14 and 16 are arranged in an overlapping relation and that they cooperate with the nozzle structures in such a way that each work piece W is positively guided for proper treatment despite the fact that the characteristics of the work treated may vary considerably. Each work piece may be very thin, extremely flexible, or quite stiff, or the edges may be curled and rather hard and despite these difficulties the conveyor belts cooperate with the nozzle units properly to feed the work.

Having described my invention, what I claim as new and desire to secure by Letters Patent of the United States is:

15. A pneumatic machine for treating hides comprising nozzle means with a nozzle discharge opening area extending the full width of a spread-out work piece, suction means along both sides of said area, and a flexible conveyor belt arranged to guide and resiliently to restrain said work piece in a path contiguous to said area and suction means.
20. A pneumatic machine for treating hides including two nozzle and suction structures, each structure extending the full width of a spread-out work piece, and flexible conveyor belts arranged to guide and resiliently to restrain said work piece in a path beneath one and over the other of said structures whereby both sides of said work piece may be treated.
25. A pneumatic machine for treating hides comprising a horizontal nozzle and suction structure extending the full width of a spread-out work piece, said structure comprising two portions joined together with spacing means between them to determine a nozzle discharge opening area, and a flexible conveyor belt arranged to guide and resiliently to restrain said work piece in a path contiguous to said area.
30. A pneumatic machine for treating hides comprising an upper and a lower nozzle and suction structure, each structure being horizontal and comprising two halves joined together to form a nozzle opening in the form of a slot with a length greater than the width of a spread-out work piece and with one lip extending beyond the other, and flexible conveyor belts arranged to guide and restrain said work piece in a path contiguous to and transverse to the extended lips.
35. A pneumatic machine for treating hides comprising nozzle means with a nozzle discharge slot extending the full width of a spread-out work piece, suction means along both sides of said slot, and a flexible conveyor belt arranged to guide and resiliently to restrain said work piece in a path leading from the front of the machine and transverse to said slot, the foremost lip of the slot being arranged to extend nearer to said path than the rearmost lip of said slot.
40. A pneumatic machine for treating hides comprising a nozzle and suction structure with a nozzle discharge area extending the full width of a spread-out work piece and suction means located beside said area, said suction means including an inlet for the admission of supplementary air, and a flexible conveyor belt arranged to guide and resiliently to restrain said work piece in a path contiguous and transverse to said structure.
45. A pneumatic machine for treating hides including horizontal upper and lower nozzle and suction structures each of which extends the full width of a spread-out work piece and comprises cast metal portions joined together to form a discharge slot between them, each structure also having suction means located beside its discharge
50. A pneumatic machine for treating hides comprising nozzle means with a nozzle discharge slot extending the full width of a spread-out work piece, suction means along both sides of said slot, and a flexible conveyor belt arranged to guide and resiliently to restrain said work piece in a path leading from the front of the machine and transverse to said slot, the foremost lip of the slot being arranged to extend nearer to said path than the rearmost lip of said slot.
55. A pneumatic machine for treating hides comprising a nozzle and suction structure with a nozzle discharge area extending the full width of a spread-out work piece and suction means located beside said area, said suction means including an inlet for the admission of supplementary air, and a flexible conveyor belt arranged to guide and resiliently to restrain said work piece in a path contiguous and transverse to said structure.
60. A pneumatic machine for treating hides comprising a nozzle and suction structure with a nozzle discharge area extending the full width of a spread-out work piece and suction means located beside said area, said suction means including an inlet for the admission of supplementary air, and a flexible conveyor belt arranged to guide and resiliently to restrain said work piece in a path contiguous and transverse to said structure.
65. A pneumatic machine for treating hides including horizontal upper and lower nozzle and suction structures each of which extends the full width of a spread-out work piece and comprises cast metal portions joined together to form a discharge slot between them, each structure also having suction means located beside its discharge
70. A pneumatic machine for treating hides including horizontal upper and lower nozzle and suction structures each of which extends the full width of a spread-out work piece and comprises cast metal portions joined together to form a discharge slot between them, each structure also having suction means located beside its discharge
75. A pneumatic machine for treating hides including horizontal upper and lower nozzle and suction structures each of which extends the full width of a spread-out work piece and comprises cast metal portions joined together to form a discharge slot between them, each structure also having suction means located beside its discharge

slot including an inlet for the admission of supplementary air, and flexible conveyor belts arranged to guide said work piece beneath one and over the other of said structures whereby both sides of said work piece may be treated.

8. A pneumatic machine for treating hides comprising nozzle means with a nozzle discharge area extending the full width of a spread-out work piece, a power operated flexible conveyor belt arranged to feed and resiliently to restrain said work piece in a path contiguous and transverse to said area, and a safety device including an element movable by undue displacement of said belt from said path to terminate the work feeding operation of the conveyor belt.

9. A pneumatic machine for treating hides including upper and lower nozzle and suction structures, each of said structures comprising two portions joined together to form a discharge slot between them, and three flexible conveyor belts arranged in overlapping relation to feed said work piece in a path leading through the machine and contiguous to the slots of said structures for treatment of both sides of the work piece.

10. A pneumatic machine for treating hides comprising upper and lower nozzle and suction structures each extending the full width of a spread-out work piece, three power operated flexible conveyor belts arranged in overlapping relation resiliently to restrain and feed said work piece in a path leading beneath one and over the other of said structures and a safety device extending beneath a run of one of said conveyor belts arranged by undue displacement of said run to reverse the direction of operation of said one of the conveyor belts. 35

11. A pneumatic machine for treating hides including upper and lower nozzle structures, said upper structure having a downwardly directed discharge, said lower structure having an upwardly directed discharge, a first horizontal conveyor belt arranged as an exposed support for a work piece as said work piece is spread out by an operator, said first belt extending beneath said upper nozzle structure, a second conveyor belt 5 contiguous to, above, and in overlapping relation with one run of said first belt and extending over said lower nozzle structure, each of said belts being power driven, and the length of the nozzle discharge area of each of said structures being in excess of the width of said work piece.

12. A pneumatic machine for treating hides including an upper nozzle structure with a discharge nozzle area directed downwardly, a lower nozzle structure with a discharge nozzle area directed upwardly, a first endless conveyor belt arranged as a partially exposed support for a hide extending beneath said upper nozzle structure, a second endless conveyor belt contiguous to, above, and in overlapping relation with the upper run of 20 said first belt and extending over said lower nozzle structure, each of said belts being power driven to feed said hide through the machine, and each of said nozzle areas extending the full width of said hide and not exceeding $\frac{3}{8}$ of a 25 square inch per linear foot as measured across 30 said hide.

JOHN G. HOLICK.
